UNITED STATES PATENT OFFICE.

EVAN R. WORCESTER, OF MARION, INDIANA, ASSIGNOR TO MACBETH-EVANS GLASS COMPANY, OF CHARLEROI, PENNSYLVANIA, A CORPORATION OF PENNSYLVANIA.

DESIGN FOR A GLASS JUG.

Application filed June 8, 1927. Serial No. 22,365. Term of patent 3½ years.

To all whom it may concern:

Be it known that I, EVAN R. WORCESTER, a citizen of the United States, residing at Marion, in the county of Grant and State of Indiana, have invented a new, original, and ornamental Design for Glass Jugs, of which the following is a specification, reference being had to the accompanying drawing, forming a part thereof.

The figure is an elevation of a glass jug, showing my new design.

I claim:

The ornamental design for a glass jug, as shown.

EVAN R. WORCESTER.
